INTERNAL TRANSFER MECHANISM FOR COUNTERS

Robert W. Herr, Fort Wayne, Ind., assignor to Bowmar Instrument Corporation, Fort Wayne, Ind.
Filed Jan. 5, 1959, Ser. No. 784,941
7 Claims. (Cl. 235—139)

This invention relates generally to counters and more particularly to counters of the internal transfer type in which the transfer mechanism is totally enclosed within the number wheels.

Internal counters conventionally comprise a plurality of successively higher order number wheels coaxially disposed on a common shaft with an intermittent motion transferring mechanism interposed between each pair of wheels, the transfer mechanism advancing the higher order wheel a predetermined angular amount responsive to a predetermined rotation of the respective lower order wheel. Thus, in one well known form of counter, commonly referred to as an odometer, each higher order number wheel is moved through one complete revolution responsive to ten revolutions of the next successive lower order number wheel, each revolution of the lower order number wheel providing one incremental advance of the next higher order number wheel. The transfer mechanisms of such prior internal counters known to the present applicant commonly comprise one of the well known intermittent motion devices such as a mutilated gear and locking cam assembly, or a geneva wheel and lock combination, arranged within the peripheral boundaries of the wheels. Such prior internal counters have generally employed internal gears (as opposed to externally toothed, i.e., spur gears) conventionally formed on the number wheels themselves, the provision of such internal gearing requiring casting or molding with consequent imperfections in the gearing. While such prior internal gearing counters have been generally satisfactory for slow speed operation, they have been found to be unsatisfactory in applications requiring high speed operation, due primarily to the lack of precision of the internal gearing, as well as the basic material from which the gears are cast or molded. Furthermore, many prior internal counters known to the present applicant have been unduly complex and thus not suitable for high quantity production. It is therefore desirable to provide a counter construction of the internal transfer type in which the transfer mechanisms incorporate spur gearing thus permitting the use of precision parts and in turn permitting high speed, heavy duty operation. It is further desirable that such a counter construction be characterized by its simplicity and ease of assembly.

It is therefore an object of this invention to provide an improved counter of the internal transfer type.

Another object of this invention is to provide an improved internal transfer mechanism for a counter characterized by the use of spur gearing.

A further object of this invention is to provide an improved internal transfer mechanism for counters which is simpler and more readily assembled and which is more suited for high speed operation than prior constructions known to the present applicant.

Further objects and advantages of this invention will become apparent by reference to the following description and the accompanying drawings, and the features of novelty which characterize this invention will be pointed out with particularity in the claims annexed to and forming a part of this specification.

My invention in its broader aspects provides a counting device having a rotatable shaft with first and second lower and higher order number wheels coaxially disposed thereon in axially spaced apart relationship. An inter-

2

mittent motion transferring mechanism is interposed between the wheels for advancing the higher order wheel a predetermined angular amount responsive to a predetermined rotation of the lower order wheel, the mechanism comprising externally toothed intermittent drive means secured to the lower order wheel on the side thereof toward the higher order wheel. A plate member is provided disposed between the lower and higher order wheels and having a central opening formed therein with the shaft rotatably extending therethrough. The plate member has a slot formed therein extending radially outward from the central opening with its end terminating short of the outer periphery and a transfer member is provided having a hub portion rotatably seated in the end of the slot with first and second portions respectively on either side of the plate member. The first portion of the transfer member cooperatively engages the intermittent drive means while the second portion cooperatively engages a spur gear secured to the higher order wheel on the side thereof toward the lower order wheel, and means are provided for restraining the plate member against rotation. In a specific embodiment of my invention, the hub portion of the transfer member has a smaller outside diameter than the outside diameters of its first and second portions so that the transfer member is thereby axially retained in the plate member slot with the engagement of the intermittent drive means and the higher order wheel gear with the first and second transfer member portions respectively radially retaining the hub portion at the end of the slot. Furthermore, the central opening of the plate member has a larger diameter than the width of the slot and the outside diameters of the first and second transfer member portions thereby to permit initial insertion of the transfer member through the central opening in the plate member and insertion of the hub portion thereof into the slot. In accordance with a further aspect of my invention, the plate member extends radially outwardly between peripheral flanges on the lower and higher order number wheels, the plate member further having a radial extension which is engaged by a frame thereby to restrain the plate member from rotation.

In the drawings, FIG. 1 is a cross-sectional view showing the preferred embodiment of my invention;

FIG. 2 is a fragmentary view in perspective, partly exploded and partly broken away, illustrating the improved transfer mechanism of my invention;

FIG. 3 is an end view of the plate member employed in the transfer mechanism of my invention; and

FIGS. 4 and 5 are end views of the mutilated gear and locking cam employed in the preferred embodiment of my invention.

Referring now to the drawings, the improved internal transfer mechanism of my invention is illustrated in connection with a counter, generally identified as 1, having four successively higher order number wheels 2, 3, 4 and 5. The lowest order number wheel 2 is mounted on a sleeve member 6 abutting an annular flange portion 7, sleeve 6 being secured to shaft 8 in any suitable manner so as to rotate therewith, such as by a key 9. Number wheel 2 is in turn secured to annular flange portion 7 of sleeve 6 by means of a suitable pin 11 and it is thus seen that the number wheel 2 is rotatable with the shaft 8.

Number wheels 3, 4 and 5 are respectively mounted on sleeves 12, 13 and 14, which are coaxially disposed on shaft 8 with a running fit so that they are respectively rotatable and axially movable with respect thereto. It will be seen that each of the number wheels 2, 3, 4 and 5 is provided with a peripheral flange 15 on which the numerals are displayed, the flanges of adjacent number wheels extending toward each other, as shown.

The improved transfer mechanism of my invention is

disposed between each adjacent pair of number wheels, i.e., 2 and 3, 3 and 4, and 4 and 5, serving in each case to advance the higher order number wheel of the respective pair a predetermined angular amount responsive to a predetermined rotation of the respective lower order number wheel. Thus, in the odometer arrangement specifically illustrated, the second order number wheel 3 will be advanced one digit responsive to each complete revolution of the lowest order number wheel 2, the second order number wheel 3 being advanced through one complete revolution in ten incremental steps responsive to ten revolutions of the lowest order number wheel 3. Likewise, number wheel 4 is advanced in the same manner with respect to number wheel 3 and the highest order number wheel 5 is advanced in the same manner with respect to number wheel 4.

In accordance with my invention, I have provided a mutilated gear 16 and a cooperating locking cam 17 coaxially mounted on the hub 6 on the side of number wheel 2 toward number wheel 3, the mutilated gear 16 and locking cam 17 being secured to number wheel 2 so as to rotate therewith by means of the pin 11. It will be observed that mutilated gear 16 and locking cam 17 are disposed within peripheral flange 15 of number wheel 2. As best seen in FIGS. 2, 4 and 5, in the specific embodiment, mutilated gear 16 comprises two teeth 18 and 19. In accordance with conventional practice, the main portion 21 of locking cam 17 has a radius substantially equal to the radius of the mutilated gear 16 to the tips of teeth 18 and 19, the cut-out or notch portion 22 of locking cam 17 having the same width as the circular pitch of the teeth 18 and 19 of the mutilated gear 16 and being slightly deeper than the whole tool depth.

A plate member 23 is provided disposed between number wheels 2 and 3, extending radially outward between the adjacent peripheral flange portions 15 as shown; plate member 23 has substantially the same radius as the radius of the number wheels 2, 3, 4 and 5. Plate member 23 has a central opening 24 formed coaxially therein through which shaft 8 extends with a running fit. Plate member 23 further has a radial extension portion 25 formed on one side thereof for a purpose to be herein-after more fully described. Plate member 23 has a slot 26 formed therein extending radially outward from the central opening 24 with its end 27 terminating short of its outer periphery; in the illustrated embodiment, slot 26 is shown as being in radial alignment with the extension 25, however, it will be readily understood that slot 26 may extend radially in some other direction.

A transfer pinion 28 is provided having a central hub portion 29 formed therein, hub portion 29 having a diameter slightly less than the width of the slot 26 of plate 23 and being seated in the slot 26 at end 27 thereof, as shown. Central hub 29 of pinion 28 divides the pinion into two parts, part 31 being disposed on the side of plate 23 toward number wheel 2 and part 32 being disposed on the side of plate 23 toward number wheel 3. Portion 31 of the transfer pinion 28 is further divided into two toothed parts 33 and 34, part 33 being cooperatively engageable with mutilated gear 16 and part 34 being cooperatively engageable with the locking cam 17. It will be observed that in the illustrated embodiment, toothed part 33 of the transfer pinion 28 comprises six teeth with toothed part 34 having three teeth, e.g., every other tooth of toothed part 33 being removed. Likewise, in the illustrated embodiment, portion 32 of transfer pinion 28 comprises six teeth which cooperatively engage a twenty-toothed gear 35. Gear 35 is coaxially disposed on the hub portion 12 and is secured for rotation with number wheel 3 by means of pin 11a.

It will now be observed that in the illustrated embodiment, by virtue of the number of teeth provided in the mutilated gear 16, transfer pinion 28 and the gear 35, each complete revolution of the number wheel 2 will result in rotational advancement of number wheel 3 through

one angular increment, ten revolutions of the number wheel 2 resulting in one complete revolution of the number wheel 3 in ten incremental steps. It will further be observed that all gearing incorporated in my transfer mechanism is of the external, i.e., spur type, and further, that each of the gear elements, namely mutilated gear 16, locking cam 17, transfer pinion 28, and gear 35, are individually formed, thus permitting their manufacture on conventional high precision gear making apparatus.

10 It will further be observed that the diameter of the central hub portion 29 of transfer pinion 28 is smaller than the outside diameter of the toothed portions 31 and 32 and therefore that the transfer pinion 28 is axially retained by virtue of the seating of the hub portion 29 in the slot 26 of the plate member 23. It will further be observed that transfer pinion 28 is radially retained against the end 27 of slot 26 by virtue of the cooperative engagement of toothed parts 33 and 34 of portion 31 with mutilated gear 16 and locking cam 17 respectively on the one hand and toothed part 32 with the gear 35 on the other hand. Furthermore, in accordance with a particular feature of my invention, it will be observed that the diameter of central opening 24 of plate member 23 is not only greater than the width of slot 26, but also somewhat greater than the diameter of portions 31 and 32 of the transfer pinion 28. Thus, in order initially to assemble my improved counter, it is merely necessary to insert transfer pinion 28 through central opening 24 of plate member 23 and then to position hub portion 29 thereof in the radially extending slot 26, after which plate member 23 may be disposed on the shaft 8. It will now further be observed that the transfer pinion 28 of my invention may be initially integrally formed as a six-tooth pinion, the hub portion 29 being thereafter turned and the alternate teeth removed by milling to form the three-toothed portion 34

35 by milling.

It will be observed that the transfer mechanisms intercoupling number wheels 3 and 4, and number wheels 4 and 5 are identical to the transfer mechanism described above which interconnects number wheels 2 and 3. Thus, mutilated gears 16a and 16b and cooperating locking cams 17a and 17b are respectively secured to number wheels 3 and 4 for rotation therewith by pins 11a and 11b and gears 35a and 35b are respectively secured to number wheels 4 and 5 by pins 11b and 11c. Likewise, transfer pinions 28a and 28b are respectively retained by plate members 23a and 23b.

My improved counter mechanism 1 is supported by a generally U-shaped frame assembly 36 having leg portions 37 and 38 and a base portion 39. Suitable bearings 41 ad 42, shown here as being of the anti-friction type, are mounted in leg portions 37 and 38 of frame 36 and rotatably support ends 43 and 44 of the shaft 8. It will also be seen that a suitable driving shaft extension 45 is provided extending axially outwardly from end 44 of shaft 8 and being thus adapted for driving the lowest order number wheel 2. Base 39 is provided with an elongated slot 46 therein in which the extensions 25 of the plate members 23 are seated, thus restraining plate members 23 against rotation.

In order to hold the number wheels 2, 3, 4 and 5 and plate members 23 in assembled relation, an annular groove 47 is formed in shaft 8 adjacent end 23. A suitable snap ring 48 is positioned in the groove 47 in turn engaging a suitable annular shim 49 which in turn engages the annular flange portion 51 of the hub portion 14 of the highest order number wheel 5. The annular shim 49 urges number wheels 5, 4 and 3 and the plate members 23 toward number wheel 2, it being observed that number wheel 2 is rigidly secured to the shaft 8 through the intermediary of hub 6 and pin 11. The thickness of annular shim 49 is suitably chosen in order to provide a close running engagement between the plate members 23 and the flanges 15 of the adjacent number wheels 2, 3, 4 and 5. It will now be seen that neither

the plate members 23 nor number wheels 3, 4 and 5 are axially restrained and are thus positioned axially, under the influence of shim 49, by virtue of their respective running engagement so that shims for positioning the individual plate members or number wheels are not needed.

The above described counter construction has been found to be extremely free running with no tendency for binding and with extremely smooth transfer of motion between the respective number wheels. It will be observed that the construction is rugged permitting the use of large ball bearings in order to withstand the high speeds for which the unit is designed. It will also again be observed that all gearing is of the spur type, individual gears being utilized which can be formed on conventional high precision gear making apparatus. It will further be observed that my device is extremely simple and is readily assembled with the employment of a minimum number of component parts.

While the specific transfer mechanism shown is of the mutilated gear and locking cam type, it will be readily apparent that my invention is not restricted to this specific form of transfer mechanism and that other well known forms of transfer mechanisms, such as the well known geneva wheel and lock type of intermittent motion transferring mechanism may be readily employed without departing from my invention.

Therefore, while I have illustrated and described a specific embodiment of this invention, further modifications and improvements will occur to those skilled in the art and I desire therefore in the appended claims to cover all modifications which do not depart from the spirit and scope of this invention.

What is claimed is:

1. In a counting device: rotatable shaft means; a first lower order number wheel coaxially disposed on said shaft means; a second higher order number wheel coaxially disposed on said shaft means and axially spaced from said first wheel; and intermittent motion transferring mechanism interposed between said first and second wheels for advancing said second wheel a predetermined angular amount responsive to a predetermined rotation of said first wheel comprising externally toothed intermittent drive means secured to said first wheel on the side thereof toward said second wheel, a plate member disposed between said wheels and having a central opening formed therein with said shaft means rotatably extending therethrough, said plate member having a slot extending radially outward from said central opening with its end terminating short of the outer periphery of said plate member, a transfer member having a hub portion rotatably seated in said slot end with first and second portions respectively on either side of said plate member, said first transfer member portion cooperatively engaging said intermittent drive means, an externally toothed spur gear secured to said second wheel on the side thereof toward said first wheel, the second portion of said transfer member including a pinion cooperatively engaging said gear to drive the same and thereby to advance said second wheel, and means for restraining said plate member against rotation, said hub portion of said transfer member having a smaller outside diameter than the outside diameters of said first and second portions whereby said transfer member is axially retained by said slot, engagement of said intermittent drive means and said gear with said first and second portions respectively of said transfer member radially retaining said hub portion thereof at said end of said slot, said central opening of said plate member having a larger diameter than the width of said slot and said outside diameters of said first and second portions of said transfer member whereby said hub portion thereof is initially positioned in said slot.

2. In a counting device: rotatable shaft means; a first lower order number wheel coaxially disposed on said

shaft means; a second higher order number wheel coaxially disposed on said shaft means and axially spaced from said first wheel; said first and second wheels having peripheral flanges respectively extending axially toward each other for display of numerals on the outer surfaces thereof; and intermittent motion transferring mechanism interposed between said first and second wheels for advancing said second wheel a predetermined rotation of said first wheel comprising externally toothed intermittent drive means secured to said first wheel on the side thereof toward said second wheel and within the peripheral flange of said first wheel; a plate member disposed between said wheels and having a central opening formed therein with said shaft means rotatably extending therethrough, said plate member having a slot extending radially outward from said central opening with its end terminating short of the outer periphery of said plate member, a transfer member having a hub portion rotatably seated in said slot end with first and second portions respectively on either side of said plate member, said first transfer member portion cooperatively engaging said intermittent drive means, an externally toothed spur gear secured to said second wheel on the side thereof toward said first wheel and within the peripheral flange of said second wheel, the second portion of said transfer member including a pinion cooperatively engaging said gear to drive the same and thereby to advance said second wheel, and means for restraining said plate member against rotation, said hub portion of said transfer member having a smaller outside diameter than the outside diameters of said first and second portions whereby said transfer member is axially retained by said slot, engagement of said intermittent drive means and said gear with said first and second portions respectively of said transfer member radially retaining said hub portion thereof at said end of said slot, said central opening of said plate member having a larger diameter than the width of said slot and said outside diameters of said first and second portions of said transfer member whereby said hub portion thereof is initially positioned in said slot.

3. In a counting device: rotatable shaft means; a first lower order number wheel coaxially disposed on said shaft means; a second higher order number wheel coaxially disposed on said shaft means and axially spaced from said first wheel; said first and second wheels having peripheral flanges respectively extending axially toward each other for display of numerals on the outer surfaces thereof; and intermittent motion transferring mechanism interposed between said first and second wheels for advancing said second wheel a predetermined rotation of said first wheel comprising externally toothed intermittent drive means secured to said first wheel on the side thereof toward said second wheel and within the peripheral flange of said first wheel, a plate member disposed between said wheels and having a central opening formed therein with said shaft means rotatably extending therethrough, said plate member extending radially between said flanges of said first and second wheels, said plate member having a radial extension portion extending beyond said flanges and a slot extending radially outward from said central opening with its end terminating short of the outer periphery of said plate member, a transfer member having a hub portion rotatably seated in said slot end with first and second portions respectively on either side of said plate member, said first transfer member portion cooperatively engaging said intermittent drive means, an externally toothed spur gear secured to said second wheel on the side thereof toward said first wheel and within the peripheral flange of said second wheel, the second portion of said transfer member including a pinion cooperatively engaging said gear to drive the same and thereby to advance said second wheel, said

hub portion of said transfer member having a smaller outside diameter than the outside diameters of said first and second portions whereby said transfer member is axially retained by said slot, engagement of said intermittent drive means and said gear with said first and second portions respectively of said transfer member radially retaining said hub portion thereof at said end of said slot, said central opening of said plate member having a larger diameter than the width of said slot and said outside diameters of said first and second portions of said transfer member whereby said hub portion thereof is initially positioned in said slot, and a frame having bearing means rotatably supporting the ends of said shaft means and a portion engaging said plate member extension thereby restraining said plate member against rotation.

4. In a counting device: rotatable shaft means; a first lower order number wheel coaxially disposed on said shaft means; a second higher order number wheel coaxially disposed on said shaft means and axially spaced from said first wheel; said first and second wheels having peripheral flanges respectively extending axially toward each other for display of numerals on the outer surfaces thereof; and intermittent motion transferring mechanism interposed between said first and second wheels for advancing said second wheel a predetermined angular amount responsive to a predetermined rotation of said first wheel comprising externally toothed intermittent drive means secured to said first wheel on the side thereof toward said second wheel and within the peripheral flange of said first wheel, a plate member disposed between said wheels and having a central opening formed therein with said shaft means rotatably extending therethrough, said plate member extending radially between and having substantially the same radius as said flanges of said first and second wheels, means urging said second wheel axially toward said first wheel whereby said peripheral flanges have a running engagement with said plate member and axially locate the same, said plate member having a radial extension portion extending beyond said flanges and a slot extending radially outward from said central opening with its end terminating short of the outer periphery of said plate member, a transfer member having a hub portion rotatably seated in said slot end with first and second portions respectively on either side of said plate member, said first transfer member portion cooperatively engaging said intermittent drive means, an externally toothed spur gear secured to said second wheel on the side thereof toward said first wheel and within the peripheral flange of said second wheel, the second portion of said transfer member including a pinion cooperatively engaging said gear to drive the same and thereby to advance said second wheel, said hub portion of said transfer member having a smaller outside diameter than the outside diameters of said first and second portions whereby said transfer member is axially retained by said slot, said central opening of said plate member having a larger diameter than the width of said slot and said outside diameters and said outside diameters of said first and second portions of said transfer member whereby said hub portion thereof is initially positioned in said slot, and a frame having bearing means rotatably supporting the ends of said shaft means and a portion engaging said plate member extension thereby restraining said plate member against rotation.

5. In a counting device: rotatable shaft means; a first lower order number wheel coaxially disposed on said shaft means; a second higher order number wheel coaxially disposed on said shaft means and axially spaced from said first wheel; said first and second wheels having peripheral flanges respectively extending axially toward each other for display of numerals on the outer surfaces thereof; and intermittent motion transferring

mechanism interposed between said first and second wheels for advancing said second wheel a predetermined angular amount responsive to a predetermined rotation of said first wheel and comprising an externally toothed mutilated gear and a cooperating external locking cam coaxially arranged on said shaft means on the side of said first wheel toward said second wheel and within said flange of said first wheel, said mutilated gear and locking cam being secured for rotation with said first wheel, an externally toothed spur gear coaxially arranged on said shaft means on the side of said second wheel toward said first wheel and within said flange of said second wheel, said spur gear being secured for rotation with said second wheel, a plate member disposed between said gears and having a central opening formed therein with said shaft means extending rotatably therethrough, said plate member having a slot extending radially outward from said central opening with its end terminating short of the outer periphery of said plate member, an integral transfer pinion having a central hub portion rotatably seated in said slot end with first and second portions respectively disposed on either side of said plate member, said first pinion portion having a first toothed part cooperatively engageable with said mutilated gear and a second toothed part cooperatively engageable with said locking cam whereby each revolution of said first wheel imparts a predetermined amount of rotational movement to said transfer pinion, said second pinion portion being toothed and cooperatively engaging said spur gear thereby driving said second wheel, and means for restraining said plate member against rotation.

6. In a counting device: rotatable shaft means; a first lower order number wheel coaxially disposed on said shaft means; a second higher order number wheel coaxially disposed on said shaft means and axially spaced from said first wheel; said first and second wheels having peripheral flanges respectively extending axially toward each other for display of numerals on the outer surfaces thereof; and intermittent motion transferring mechanism interposed between said first and second wheels for advancing said second wheel a predetermined angular amount responsive to a predetermined rotation of said first wheel and comprising an externally toothed mutilated gear and a cooperating external locking cam coaxially arranged on said shaft means on the side of said first wheel toward said second wheel and within said flange of said first wheel, said mutilated gear and locking cam being secured for rotation with said first wheel, an externally toothed spur gear coaxially arranged on said shaft means on the side of said second wheel toward said first wheel and within said flange of said second wheel, said spur gear being secured for rotation with said second wheel, a plate member disposed between said gears and extending radially outward between said flanges, said plate member having a radial extension and a central opening formed therein with said shaft means extending rotatably therethrough, said plate member having a slot extending radially outward from said central opening with its end terminating short of the outer periphery of said plate member, an integral transfer pinion having a central hub portion rotatably seated in said slot end with first and second portions respectively disposed on either side of said plate member, said first pinion portion having a first toothed part cooperatively engageable with said mutilated gear and a second toothed part cooperatively engageable with said locking cam whereby each revolution of said first wheel imparts a predetermined amount of rotational movement to said transfer pinion, said second pinion portion being toothed and cooperatively engaging said spur gear thereby driving said second wheel, said hub portion of said transfer pinion having a smaller diameter than the diameter of said first and second pinion portions whereby said transfer pinion is axial-

ly retained by said plate member slot, engagement of said first and second pinion portions with said gears and locking cam respectively radially retaining said transfer pinion hub portion at said end of said slot, said central opening of said plate member having a diameter larger than the width of said slot and the diameters of said first and second pinion portions whereby said transfer pinion is initially inserted through said central opening and said hub portion thereof positioned in said slot; and a frame having bearing means respectively rotatably supporting the ends of said shaft means and a portion engaging said plate member extension to restrain the same against rotation.

7. In a counting device: a rotatable shaft; a first lower order number wheel coaxially secured to said shaft for rotation therewith; a plurality of successively higher order number wheels coaxially arranged on said shaft for rotational and axial movement with respect thereto; each of said wheels having a peripheral flange for display of numerals on the outer surface thereof, the flanges of adjacent wheels extending axially toward each other; intermittent motion transferring mechanism interposed between each pair of adjacent wheels for advancing the higher order wheel a predetermined angular amount responsive to a predetermined rotation of the lower order wheel, each said transfer mechanism comprising an externally toothed mutilated gear and cooperating external locking cam coaxially arranged on said shaft on the side of the lower order wheel toward the higher order wheel and within the flange of the lower order wheel, said mutilated gear and locking cam being secured for rotation with the lower order wheel, an externally toothed spur gear coaxially arranged on said shaft on the side of the higher order wheel toward the lower order wheel and within the flange of the higher order wheel, said spur gear being secured for rotation with the higher order wheel, a plate member disposed between said gears and extending radially outwardly between the flanges of the respective wheels and having substantially the same radius, said plate member having a radial extension and a central opening formed therein with said shaft extending rotatably therethrough, said plate member having a slot extending radially outwardly from said central open-

ing with its end terminating short of the outer periphery of said plate member, an integral transfer pinion having a central hub portion rotatably seated in said slot end with first and second portions respectively disposed on either side of said plate member, said first pinion portion having a first toothed part cooperatively engageable with said mutilated gear and a second toothed part cooperatively engageable with said locking cam whereby each revolution of the lower order wheel imparts a predetermined amount of rotational movement to said transfer pinion, said second pinion portion being toothed and cooperatively engaging said spur gear thereby driving the higher order wheel, said hub portion of said transfer pinion having a smaller diameter than the diameter of said first and second pinion portions whereby said transfer pinion is axially retained by said plate member slot, engagement of said first and second pinion portions with said gears and locking cam respectively radially retaining said transfer pinion hub portion at said end of said slot, said central opening of said plate member having a diameter larger than the width of said slot and the diameter of said first and second pinion portions whereby said transfer pinion is initially inserted through said central opening and said hub portion thereof positioned in said slot; a generally U-shaped frame having bearing means respectively carried by its leg portions and rotatably supporting the ends of said shaft with said wheels therebetween, the center portion of said frame having means engaging the extensions of said plate members thereby restraining the same against rotation; and means on the end of said shaft adjacent the highest order number wheel and engaging the same adapted to retain all of said wheels and said plates so that said plates have a running engagement with the respective flanges.
